(57) **CLAIM**

The ornamental design for a modular sofa as shown and described.

DESCRIPTION

FIG. 1 is a front, left, and top perspective view of a first arrangement of a modular sofa showing my new design, comprising two curved arms, and a body with a cushion and a backrest.

FIG. 2 is a front, left, and top perspective view of a second arrangement thereof, comprising two curved arms, and two bodies with two cushions and two backrests.

FIG. 3 is a front, left, and top perspective view of a third arrangement thereof, comprising two curved arms, three bodies with three cushions and three backrests, and two ottoman stools.

FIG. 4 is a front, left, and top perspective view of a fourth arrangement thereof, comprising a corner ottoman stool with three cushions and three backrests.

FIG. 5 is a front, left, and top perspective view of a fifth arrangement thereof, comprising two curved arms, five bodies with five backrests, an ottoman stool, and a corner ottoman stool with three cushions and three backrests.

FIG. 6 is a front elevation view of FIG. 5.

FIG. 7 is a rear elevation view of FIG. 5.

FIG. 8 is a left side elevation view of FIG. 5.

FIG. 9 is a right side elevation view of FIG. 5.

FIG. 10 is a top plan view of FIG. 5.

FIG. 11 is a bottom plan view of FIG. 5.

FIG. 12 is a front, left, and top perspective view the body with the cushion and the backrest of the modular sofa in FIG. 1.

FIG. 13 is a front elevation view thereof.

FIG. 14 is a rear elevation view thereof.

FIG. 15 is a right side elevation view thereof, the left side view being a mirror image thereof.

FIG. 16 is a top plan view thereof.

(Continued)

FIG. 17 is a bottom plan view thereof.

FIG. 18 is a front, left, and top perspective view the ottoman stool of the modular sofa in FIG. 1 in one state.

FIG. 19 is another front, left, and top perspective view the ottoman stool of the modular sofa in FIG. 18 in another state.

FIG. 20 is a front elevation view of FIG. 18.

FIG. 21 is a rear elevation view of FIG. 18.

FIG. 22 is a left side elevation view of FIG. 18, the right side view being a mirror image thereof.

FIG. 23 is a top plan view of FIG. 18.

FIG. 24 is a bottom plan view of FIG. 18.

FIG. 25 is a front, left, and top perspective view of the corner ottoman stool of the modular sofa in FIG. 5 in one state.

FIG. 26 is another front, left, and top perspective view of the corner ottoman stool of the modular sofa in FIG. 25 in another state.

FIG. 27 is a front elevation view of FIG. 25.

FIG. 28 is a rear elevation view of FIG. 25.

FIG. 29 is a left side elevation view of FIG. 25, the right side view being a mirror image thereof.

FIG. 30 is a top plan view of FIG. 25; and,

FIG. 31 is a bottom plan view of FIG. 25.

The broken lines in the figures depict portions of the modular sofa that form no part of the claimed design.
